UNITED STATES PATENT OFFICE.

ALFRED L. EVANS, OF BALTIMORE, MARYLAND.

VENTILATING WINDOW-SASH.

1,256,452.

Specification of Letters Patent. Patented Feb. 12, 1918.

Application filed May 12, 1916. Serial No. 97,127.

To all whom it may concern:

Be it known that I, ALFRED L. EVANS, a citizen of the United States, residing at Baltimore, in the State of Maryland, have 5 invented new and useful Improvements in Ventilating Window-Sashes, of which the following is a specification.

In carrying out the present invention, it is my purpose to provide a ventilating window sash wherein supplemental sashes may be swung outwardly from the main sash to provide an opening for the admission of air into the room or compartment and wherein the glass will be arranged in sections, so formed and correlated as to prevent the admission of rain, snow or the like to the room or compartment when the glass is swung outwardly from the sash.

With the above and other objects in view, 20 the invention consists in the construction, combination and arrangement of parts hereinafter set forth in and falling within the scope of the claims.

In the accompanying drawings;

25 Figure 1 is a front elevation of a window sash constructed in accordance with the present invention.

Fig. 2 is an edge elevation of the same showing the parts in open position.

30 Fig. 3 is a vertical sectional view therethrough.

Fig. 4 is a horizontal sectional view through the same.

Fig. 5 is an enlarged detail view.

35 Fig. 6 is a similar view.

Referring now to the drawings in detail, 1 designates a main sash or frame embodying top and bottom rails 2 and 3 respectively and side stiles 4. This sash 1 is adapted to be mounted in a window casing and is capable of vertical sliding movement therein as usual, and the inner surface of the bottom rail of the sash is provided with a finger hold 5 to facilitate the raising and lowering of the sash. In the present instance, the outer surfaces of the top, and bottom rails and the side stiles of the sash contiguous to the inner edges of such rails and stiles are rabbeted as at 6 and arranged 45 within the sash adjacent to the respective stiles thereof are L-shaped frames 7. The vertical bar of each frame 7 is disposed within the rabbet of the adjacent stile and its base is connected to such stile by means of vertical hinges 8 so that the frame may 50 be swung into and out of the main sash.

These hinges 8 are countersunk in the side stile of the sash. The lower horizontal bars of the frames 7 are disposed within the rabbeted portion of the bottom rail 3. Suitably secured in each frame 7 is a right angular triangular section of glass 11 or other transparent material and the inclined edges of the glass sections confront each other. Each frame 7 and glass 11 carried thereby 65 forms what will be termed a triangular supplemental sash. The glass sections carried by the frames 7 are of less width than the sash 1. Within the sash 1 is a relatively large trapezoidal frame 9 embodying a top bar, side bars depending from the top bar and converging toward each other at their lower ends, and a bottom bar connecting the side bars at the lower extremities thereof. The converging side bars of the frame 9 70 overlap the glass 11 in the frames 7 and the lower bar of the frame 9 is adapted to fit into the rabbet in the bottom rail of the sash, while the top bar fits into the rabbet in the upper rail of the sash. The top bar 75 of the frame 9 is connected to the top rail of the sash by means of horizontal hinges 10 that are countersunk in the upper rail of the sash frame. Mounted in the frame 9 is a plate 11' of glass or other transparent material and the inclined edges of the glass sections 11 bear against the under surface of the plate 11'. The frame 9 and plate 11' 80 form what may also be termed a trapezoidal supplemental sash.

85 In the present instance, the lower bars of the respective frames 7 are equipped with hook-shaped keepers 12 having rather long upstanding bills which slidably engage the bottom bar of the frame 9 so that in the outward and inward movements of the frame 9 90 corresponding movements will be imparted to the frames 7.

95 In this form of my invention, the bottom bar of the frame 9 is equipped centrally with an eye 13 and connected to the eye 13 is one end of a strip 14 formed with openings 15 spaced apart longitudinally of the strip. Mounted in the inner edge of the bottom rail of the sash is a pin 16 disposed in line 100 with the eye 13, while arranged to one side of the pin 16 is a pin 17. Formed on one edge of the strip 14 is a depending lip 18 designed to overlie the bottom rail of the sash 105 in one position of the strip.

110 In practice, when it is desired to ventilate the room or compartment without raising

the sash in the window casing. the frame 9 is swung outwardly from the sash in a vertical plane, thereby automatically swinging the frames outwardly in a horizontal plane, 5 and in the outward movement of these frames a space is formed between the supplemental frames and the bottom rail of the sash whereby the air may pass through the sash and into the compartment. When the 10 frames 9 and 7 are swung outwardly to the desired position, the strip 14 is moved to engage one of the openings 15 with the pin 16 so as to hold the frames in open position.

The side bars of the frame 9 are preferably formed with outwardly projecting flanges 19 lined with rubber, felt or the like that frictionally engage the glass carried by the frames 7 so as to form weather proof joints between the frames 9 and 7 to prevent 20 the entrance of rain, snow and the like to the compartment when the frames are in open or closed positions.

To close the frame, the strip 14 is disengaged from the pin 16 and pulled inwardly, 25 thereby swinging the frames 9 and 7 into the sash. The opening at the inner end of the strip 14 is offset from the remaining openings and when the frames have been drawn into the sash, this offset opening is engaged 30 with the pin 16 and the strip 14 swung about the pin 16 as a fulcrum, thereby drawing the frame tightly into the sash. Succeeding the swinging of the strip 14 one of the openings 15 is engaged with the pin 17 and the lip 18 35 engaged with the bottom rail of the sash in order to hold the strip 14 against accidental movement.

The upper end portion of the side bars of the frame 9 are relatively thick as shown in 40 the drawings so that the upper end of the glass sections 11 in the frame 7 will be completely overlapped to prevent the passage of dirt, air, rain and the like through the window. The lower bars of all of the frames 45 mounted in this sash are cut out at the overlapping portions of the frame so that the glass sections carried by the side frames will bear against the glass sections carried by the intermediate frame.

50 While I have herein shown and described the preferred form of my invention by way of illustration, I wish it to be understood

that I do not limit or confine myself to the precise details of construction herein described and delineated, as modification and 55 variation may be made within the scope of the claims and without departing from the spirit of the invention.

I claim:

1. In a ventilating window, a pair of triangular sashes hinged at the sides of the window opening for horizontal swinging, and a third sash hinged above the triangular sashes for vertical swinging and adapted when in extended position to be supported 65 upon the hypotenusal edges of said pair of sashes.

2. A pair of triangular sashes mounted at the sides of a window opening on vertical hinges for horizontal swinging, a third sash supported on horizontal hinges at the top of the window opening for vertical swinging, its sides overlying the first named sashes and adapted to be supported upon their free edges when all sashes are open, and connections on the lower bars of the first named sashes slidably engaging the last named sash as all sashes are moved to closed position.

3. In a ventilating window, the combination with a main frame; of triangular sashes hinged to the side stiles thereof for horizontal swinging, and a third sash hinged for vertical swinging and with its sides overlying the triangular sashes in any position of parts and abutting their hypotenusal edges 85 when the sashes are open.

4. In a ventilating window, the combination with a frame; of a right-angular supplemental frame hinged in each side stile thereof and adapted to close into the bottom rail, triangular glasses in these frames, a fourth frame hinged in the top rail with its sides adapted to overlie said glasses and its lower bar to lie against the bottom rail when this frame is closed, a glass in the fourth frame, and hook-shaped keepers on the lower bars of the said right-angular frames whose bills slidably engage the lower bar of said fourth frame, for the purpose set forth.

In testimony whereof I affix my signature. 100
ALFRED L. EVANS.
